United States Patent Office

Des. 190,879
Patented July 11, 1961

190,879

CRUMB STRAINER

Luella Ernst Kessler, 717 Apache, Grand Prairie, Tex.

Filed Nov. 21, 1960, Ser. No. 62,912

Term of patent 14 years

(Cl. D44—29)

Fig. I

Fig. II

Fig. III

Fig. IV

Fig. V

FIG. I is a perspective view of the crumb strainer showing my new design;

FIG. II is a top plan view thereof;

FIG. III is a side elevational view thereof;

FIG. IV is a bottom plan view thereof; and

FIG. V is a front end view thereof.

I claim:

The ornamental design for a crumb strainer, substantially as shown.
